Primary Examiner—B. J. Bullock

(74) Attorney, Agent, or Firm—Wallenstein & Wagner, Ltd.

(57) **CLAIM**

I claim the ornamental design for a handle, as shown and described.

DESCRIPTION

FIG. 1 is a perspective view of a handle, embodying the new design;

FIG. 2 is a front elevation view of the handle;

FIG. 3 is a left side elevation view of the handle;

FIG. 4 is a right side elevation view of the handle;

FIG. 5 is a top plan view of the handle;

FIG. 6 is a bottom plan view of the handle; and,

FIG. 7 is a rear elevation view of the handle;

Portions shown in broken lines are for illustrative purposes only and form no part of the claimed design.
